UNITED STATES PATENT OFFICE.

PETER NEUKIRCHEN, OF CHICAGO, ILLINOIS.

MUCILAGE-SPREADER.

1,164,848.

Specification of Letters Patent. Patented Dec. 21, 1915.

Application filed February 9, 1914. Serial No. 817,393.

To all whom it may concern:

Be it known that I, PETER NEUKIRCHEN, a citizen of the United States, and a resident of Chicago, county of Cook, and State of Illinois, have invented certain new and useful Improvements in Mucilage-Spreaders, of which the following is declared to be a full, clear, and exact description.

This invention relates to mucilage spreaders and designs to provide a bottle or container for mucilage or other liquid paste and having a stopper provided with a valve controlled discharge aperture which is opened by pressure against the valve or a protruding portion thereof.

One of the principal objects of this invention is to provide a spring at the bottom of the bottle for seating the valve, which spring remains in the mucilage when the bottle or container is set upright, whereby the possibility of the spring becoming clogged with dried mucilage is avoided.

Another object is to provide a mucilage spreading tongue on the stopper by means of which the mucilage may be spread evenly over the object on which it is deposited.

Another object is to provide a simple and convenient self-contained mucilage spreader which shall be of comparatively inexpensive construction.

With all of these objects and advantages in view, the invention consists in the several novel features hereinafter fully set forth in the following specification and more definitely pointed out in the claim.

The invention is clearly illustrated in the drawing furnished herewith in which:—

Figure 1 is a longitudinal section through a mucilage spreader embodying the preferred form of the invention; Fig. 2 is a plan or top view thereof; Fig. 3 is a side view of the mucilage spreading tongue and one member of the stopper; Fig. 4 is a perspective view of said mucilage spreading tongue and member of the stopper; Fig. 5 is a side view of the valve and a fragment of its valve stem; Fig. 6 is a longitudinal section of a modified form of the invention showing the same in an inverted position with the valve open to permit of the discharge of a quantity of the mucilage, and Fig. 7 is a section through a modified form of support for the spring.

In the embodiment of the invention illustrated in the drawing and particularly in

Figs. 1 to 5, inclusive, 10, designates a bottle or container which may be constructed of glass or any other suitable material as is desired, said container having an open neck 11, at its upper end. The bottle may be of any suitable size and shape which may be conveniently handled. The open neck of the bottle is closed by a stopper 12, which may comprise an annular cork portion 13, fitting in the open neck of the bottle and a hollow dome shaped member 14, secured in the central opening of the cork. Said dome shaped member of the stopper has a central aperture 15, at its extreme upper end which is closed by a valve 16, carried by a valve stem 17, which projects down into the bottle and terminates near its lower end. A coiled compression spring 18, is secured to the lower end of the valve stem and bears against the bottom of the bottle, which may be provided with a central upwardly projecting lug 19, for holding the spring against lateral displacement on the bottom of the bottle. The valve stem may comprise a wire rod of sufficient length to extend from the valve to a point near the bottom of the bottle and may be struck up to provide flattened shoulders 20, for the spring 18, to bear against. The valve 16, is arranged to seat against the inner face of the dome 14, and has a rounded end portion 21, which projects out through the aperture 15. Pressure upon the end portion of the valve unseats the valve and permits the escape of mucilage whenever the bottle is inverted.

Secured to the stopper is a mucilage spreading tongue 22, which is shown as comprising a piece of light gage sheet metal, one part of which rests on the cork and is formed with an opening surrounded by a down turned flange 23; the dome shaped member extends through said opening and is formed with an annular bead 24, which bears upon the upper face of that portion of the mucilage spreading tongue which rests upon the cork. That portion of the tongue which is employed in spreading the mucilage is bent downward from the other portion as is clearly indicated at 22^a in Figs. 1 and 4.

In the modified form illustrated in Fig. 6, the valve stem 17^a is shown as guided in a stirrup like strip of metal 19^a. In this case, the spring 18^a is confined between the end

portion 19^a of the stirrup and the shoul-
dered portion 20^a of the valve stem. Said
stirrup like structure is secured in the stop-
per either by friction or by any other suit-
able means as is found desirable.

In place of forming the lug 19, on the
bottom of the bottle, the lug may be formed
on a strip of metal 10^a, which may be placed
on the bottom. This arrangement is illus-
trated in Fig. 7; its length should be ap-
proximately equal to the diameter of the
bottom, whereby it may be kept in place by
contact with the side wall of the bottle.

In use, the bottle is filled, or partially
filled, with mucilage or any other liquid
paste 25, and to apply mucilage to a surface,
the bottle is inverted and the protruding
portion 21, of the valve pressed down upon
the surface which is to receive the mucilage,
thus unseating the valve and permitting a
quantity of mucilage to flow out through the
aperture 15. Thereafter, the mucilage may
be spread evenly over the surface by rub-
bing the mucilage spreading tongue over
the mucilage. The tongue being flexible, it

acts somewhat in the manner of a brush
when used in spreading the mucilage.

More or less variation of the details of
construction is possible without departing
from the spirit of this invention, and I de-
sire, therefore, not to limit myself to the
exact forms of construction shown and de-
scribed, but intend in the following claim
to point out all of the invention disclosed
herein.

I claim as new and desire to secure by
Letters Patent:

An attachment for mucilage bottles com-
prising a cap for the bottle having an exit
port, a spreader tongue carried by said cap,
a valve to normally close said port, a valve
stem carried by the valve, a spring to hold
the valve normally closed but permitting the
valve to open by contact with the surface to
be pasted to permit the mucilage to pass
through said port.

PETER NEUKIRCHEN.
